UNITED STATES PATENT OFFICE.

RHODES SEWELL, OF BANNING, GEORGIA.

GAME.

1,406,691.

Specification of Letters Patent. Patented Feb. 14, 1922.

Application filed March 26, 1921. Serial No. 455,753.

To all whom it may concern:

Be it known that I, RHODES SEWELL, a citizen of the United States, residing at Banning, in the county of Carroll and State 5 of Georgia, have invented a new and useful Game, of which the following is a specification.

This invention relates to games, one of its objects being to provide a game board 10 over which a game piece is adapted to be moved space by space according to the number of moves designated by dice or other chance devices, the playing field on said board being divided into a number of spaces 15 equal to the number of days in the year and certain of these spaces being provided with designations appropriate to the season of the year to which the spaces belong and which designations affect the moves of the 20 player.

A further object is to provide a game board having the spaces in the playing field arranged in concentric circles, there being points in the circles where the game pieces 25 are shifted from one circle to the other, these points being suitably designated.

With the foregoing and other objects in view which will appear as the description proceeds, the invention resides in the combination and arrangement of parts and in the details of construction hereinafter described and claimed, it being understood that, within the scope of what is claimed, changes in the precise embodiment of the 35 invention shown can be made without departing from the spirit of the invention.

In the accompanying drawing, which is a plan view of the game board, the preferred form of the invention has been shown.

40 Referring to the drawing by characters of reference 1 designates the game board on which is outlined a circular field 2. This field is divided by concentric circles 3 into concentric series of spaces divided by radial 45 lines as shown.

A space from which play is to be started is outlined on the board 1 outside of the playing field, as indicated at 4 and this space is coupled to one of the spaces in the 50 outer circular row.

The game as illustrated is designed to bring to mind various incidents of farm life likely to occur throughout a year and beginning with the space in the outer circular row 55 adjacent the point of communication with

the starting space 4 the spaces in said outer row are numbered from 1 to 31 to indicate the 31 days of January and are then successively numbered to indicate the days of the month of February. The remaining 60 spaces are numbered to indicate the days of the month of March, and where the last numbered space appears in the outer circle it is coupled to the first space in the next adjoining circular series by a suitable indicator 65 such as shown at 5. For example if the last space of the outer circle is numbered to indicate the seventh of March, the first space in the next adjoining circle will indicate the eighth of March. The spaces in the second 70 circle are then dated consecutively up to the last space of said circle whereupon another indicator 5 directs the player to the third circular row wherein the dates are continued.

This arrangement is followed throughout 75 the field from the periphery thereof to the center where a large space is provided containing the word "Finished" and the numeral "31" indicating that the player reaching the central space has completed his 80 moves and that said space represents the 31st day of December or the last day of the year. The various holidays are indicated in the proper spaces and these spaces contain data provided with suitable penalties or rewards given the player whose game piece is brought to a stop on one of said spaces. Other selected spaces can be provided with data denoting other penalties or rewards all of which are indicated by some 85 situation or happening likely to be met with on a farm during the different seasons of the year. Thus the playing of the game, which is effected by throwing dice or spinning a wheel to indicate the number of 90 moves of a game piece, not only affords considerable amusement to the players but also is instructive in that it brings home forcibly to the players the nature of farm life throughout the year. 100

What is claimed is:

1. In a game a game board having a playing field made up of concentric series of spaces, there being an indicator designated on the field between one space of each series 105 and the next succeeding space in the adjoining series, said spaces being designated from the first space in the outer series to the last space in the inner series to indicate successively the days of the year, there being 110

designated in certain of the spaces penalties or rewards appropriate to the season of the year to which said spaces belong.

2. In a game a game board having a circular playing field made up of concentric circular series of spaces, there being indicating devices on the playing field for coupling the last space of each series to the first space of the next adjoining series inwardly therefrom, all of the spaces from the first space in the outermost series to the innermost space on the playing field being designated successively to indicate the days of the months and year, there being displayed

in certain of the spaces penalties and rewards appropriate to the season of the year to which said spaces belong, there being a space outside of the playing field and indicating the point of beginning, said space communicating with the first space of the outer series.

In testimony that I claim the foregoing as my own, I have hereto affixed my signature in the presence of two witnesses.

RHODES SEWELL.

Witnesses:
